ATTORNEY.

UNITED STATES PATENT OFFICE.

RUPERT SWINNERTON, OF MINNEAPOLIS, MINNESOTA.

AUTOMOBILE GARAGE.

Application filed March 31, 1920. Serial No. 370,121.

To all whom it may concern:

Be it known that I, RUPERT SWINNERTON, a citizen of the United States, and resident of Minneapolis, county of Hennepin, State 5 of Minnesota, have invented certain new and useful Improvements in and Relating to Automobile Garages, of which the following is a specification.

This invention relates to certain improvements 10 in garages or storage buildings for automobiles and other vehicles; and the objects and nature of the invention will be readily understood by those skilled in the art in the light of the following explanations of the accompanying drawings illustrating what I now believe to be the preferred embodiments or mechanical expressions of my invention from among other forms, constructions and arrangements within 15 20 in the spirit and scope thereof.

An object of the invention is to increase to the maximum the automobile parking or storage capacity of garages and storage parks and the ease and facility with which 25 automobiles can be manipulated, handled, parked and stored on, and driven onto and from parking and storage floors.

With these and other objects in view, my invention consists in certain novel features 30 in construction, arrangement and combination as more fully and particularly set forth and specified hereinafter.

Referring to the accompanying drawings:

Fig. 1 shows, somewhat diagrammatically, 35 the floor plan of a garage embodying my invention.

Fig. 2 is a vertical section of a garage embodying my invention, the garage being shown somewhat diagrammatically and on 40 a greatly reduced scale.

Fig. 3 shows somewhat diagrammatically, a modified form of ground or floor plan for a garage embodying my invention.

Figs. 4, 5, and 6 are detail views.

In the embodiments illustrated, I provide 45 a building or enclosure 1 of any suitable dimensions and construction, although for purposes of economy and to follow conventional lines of building or garage architecture, I usually erect a rectangular building having vertical side walls and any suitable roof to enclose and cover my parking and storage floor, and this building can enclose or be provided with several automobile 50 55 parking or storage floors embodying my in-

vention; for instance, a ground floor and an upper floor that can be reached by either elevator or inclined runway from the lower floor, and furthermore in exceedingly congested urban centers my parking or storage 60 floor can be utilized in open or out-of-doors parking or storage parks.

In the particular example illustrated, the garage building 1, is provided with any suitably arranged and constructed supports 65 for the roof 2, although I happen to show center pillars or uprights 3 for this purpose. My invention, however, is not limited to such roof supports.

The particular building shown has a 70 ground floor entrance and exit opening 4, located approximately at the center of the width of the building front, although I do not wish to so limit my invention. This door or opening 4 is for the entrance and exit of 75 automobiles to and from the parking or storage floor.

The building is provided with a substantially horizontal level parking and storage floor to and from which automobiles 80 can travel through door or opening 4, and on which automobiles can be manipulated or propelled and stored or parked, and this floor includes a suitable fixed, stationary or permanent part 5 composed of concrete, 85 earth or other suitable material, and a suitable traveling or transporting horizontal section or portion 6, the top surface of which is substantially flush with the adjacent horizontal fixed floor surfaces. The 90 traveling floor portion 6, is in this instance, annular in form, and of such radial width as to permit parking or storage of automobiles thereon when arranged radially with respect thereto, and the dimensions of this 95 traveling portion 6 with respect to the fixed portions 5 of the floor, are such as to provide fixed floor storage and parking places within the inner circle of the traveling floor and also outside of the outer circle of said 100 traveling floor.

The traveling floor is rotatable horizontally around a vertical axis located approximately at the central portion of the building or parking floor as an entirety, and in 105 the examples illustrated, the concrete floor is formed with a depressed annular trough or channel 7, to receive said annular floor or table 6 and the supporting means therefor.

On the bottom of this channel, I show a 110

pair of fixed concentric annular horizontal rails 8, and a fixed annular gear rack 9, and the annular floor section or table is supported by wheels traveling on said rails and 5 is propelled by a vertical shaft carried by the table and rotating a gear meshing with said rack.

The annular table can be of various constructions, although in the examples illustrated, I show the same made up of an annular series of radial trucks, platforms or sections suitably coupled together and each having supporting wheels traveling on the rails. Each such truck consists of a flat or 10 horizontal top platform 6^a (forming a radial section of the traveling floor or table) having edge depending flanges or aprons 6^b and fixed radial axles 6^c on which supporting wheels 6^d are freely and independently 15 rotatable. The axles are fixed in suitable depending platform supporting bolsters and the wheels 6^d travel on the rails 8. The trucks are arranged edge to edge and are coupled together by suitable bolts or other 20 couplings 6^e through the medium of the depending aprons 6^b.

The traveling table can be provided with a rotary shaft 6^f mounted in one of the trucks or sections thereof and at its lower 25 end having gear 6^g fixed to the shaft and meshing with rack 9. Above the table this shaft is equipped with means for rotating the same to propel the table. This shaft can be driven manually or by power, and 30 if so desired each table can be equipped with a power driven table propelling shaft and with a manually actuated table propelling shaft. I show the shaft 6^f provided with handles 6^h for rotating the same, while 35 at a different portion of the table I show another table propelling shaft 6ⁱ equipped with an electric motor M for driving the same. However, I do not wish to so limit my invention.

40 The annular traveling table is so arranged with respect to the floor as an entirety as to provide the approximately annular parking and storage area A of the fixed floor surrounding the table, and the approximately 45 annular parking and storage area B of the fixed floor surrounded by the table. Within and surrounded by the annular area B I preferably provide the center area C of the fixed floor in which the roof posts 3 (if 50 employed) can be located and which can be otherwise utilized for a driveway and as a gasoline and supply station. The area D of the fixed floor opposite or adjacent to the garage entrance opening 4 and included 55 in the circle of the annular storage space A, forms, what might be termed a driveway vestibule, and in line therewith a driveway E extends diametrically across the areas B, C, so that the radial portion of the traveling

table between area D and driveway E, constitutes a connecting driveway between floor areas D and E.

Where the floor or the building is approximately rectangular in form, the four corner areas F beyond or outside of the 70 annular area A, can be utilized for automobile storage, particularly for so-called "dead" storage.

Where the traveling table comprises 75 trucks or platforms 6^a as in the particular examples illustrated, each such platform 6^a is of sufficient length and breadth to accomodate an automobile for parking thereon, and to permit parking of automobiles 80 on the table, one car on each such platform of the table where the automobiles are arranged radially with respect to the axes of rotation of the table, and also to permit rotation of the table with the automobiles 85 thereon for the purpose of transporting the automobiles for delivery at various points in the areas A, B, or to receive or deliver automobiles at areas D, E.

In other words, the radial width of the traveling table is sufficient to enable said 90 table to carry and transport motor cars when arranged radially of the table, and to enable the table to receive a large number 95 of radially arranged motor cars located side by side.

The annular areas A, B, will also receive 100 large numbers of motor cars radially arranged and located side by side so that the cars can be propelled radially of the table 105 to and from the table and the annular 110 spaces A, B.

I preferably visibly divide the top face 115 of the table, and the various storage areas A, B, F, into radial motor car receiving stalls or spaces, one for each radially arranged car, as indicated in the drawings. These stalls can be thus visibly indicated in any suitable manner as by paint lines, or by peculiar formation of the concrete or other 120 floor surface, or by structural means such as bars, chains etc. The motor car spaces or stalls in the table itself can be visibly indicated by the boundaries of the platforms 6^a, where the table is thus built up of clearly defined sections. The driveways E, D, can 125 also be visibly defined as indicated in the drawings, in any suitable manner, as by paint lines or by structural formation of the concrete or other floor surface.

A motor car entering the floor through 130 opening 4 and driveway entrance D, is driven over the normally stationary traveling table and along the driveway E and onto the table at the far end of the driveway 135 and there brought to rest, if such car is to 140 be parked in any stall or area outside of the outer circle of the traveling table. The traveling table is then propelled until the

motor car is brought in line with the stall in annular area A where the car is to be parked. The table is then brought to rest and the car is propelled therefrom into said stall. When 5 the car is to be taken from the garage, it is backed from the stall onto the table, and the table is then rotated until the car is in line with driveway entrance D whereupon the table is stopped and the car can be driven 10 forward from the garage. The car on entering the garage can be driven onto the table from driveway entrance D and then brought to rest, and the table can be rotated to bring the car into line with either a stall 15 in annular area B or a stall in annular area A. The car can then be backed from the table to the stall in area A, or driven forward to the stall in area B. However, the rear car can be delivered by the table from either 20 stall, so that the car can be driven forward from the table at the driveway entrance D, in leaving the garage, and by utilizing the driveway E, and stopping the cars on the table either at driveway entrance D, or at 25 the far end of driveway E, cars can be delivered for direct forward driving from the garage, without necessitating turning the cars around except through transportation by the table.

30 Cars can be parked and stored in the various areas A, B, and removed therefrom without disturbing other parked cars, and cars can also be stored on the table itself without disturbing other cars and without interfering with the reception and delivery of cars 35 by the table so long as one or two stalls on the table are unoccupied by stored or parked cars.

By arranging the table 6 eccentrically 40 with respect to outer annular storage area A', Fig. 3, I can arrange radial stalls *a* gradually increasing in length from the entrance driveway D toward the far end of the driveway E to provide for cars of different 45 lengths, whereby a saving in space is attained.

It is evident that various changes, modifications and variations might be resorted to without departing from the spirit and 50 scope of my invention and hence I do not wish to limit myself to the exact disclosures hereof.

Desiring to secure the broadest protection 55 legally possible, what I claim is:—

1. A vehicle parking and storage floor embodying an annular rotary vehicle distributing and collecting area; a surrounding adjacent annular floor area and a central floor area, the arrangement being such 60 that vehicles may be distributed directly from said rotary area to storage position on the adjacent floor areas.

2. A vehicle parking and storage floor embodying an annular rotary vehicle storage and transporting table, a vehicle stor- 65

age and driveway area surrounded by said table, and a vehicle storage and driveway area adjacent to and surrounding said table, whereby vehicles may be distributed directly to said storage areas by rotating said table. 70

3. A vehicle parking and storage floor embodying fixed and rotary vehicle parking and driveway areas, the rotary area embodying an annular vehicle transporting 75 and parking table adjacent to and surrounded by said fixed areas.

4. A garage having a vehicle parking and driveway floor embodying an annular rotary vehicle transporting table constructed 80 and arranged to carry a plurality of radially arranged vehicles, whereby a vehicle may be transported to position for discharge directly from said table to the desired section of the adjacent fixed parking and driveway floor. 85

5. A parking floor for vehicles embodying an annular rotary table constituting a portion of the floor area, a fixed floor area surrounded by said table, and a fixed floor 90 area surrounding said table, said table and fixed areas being so arranged that vehicles can travel from area to area and across said table, said table constructed and arranged to transport vehicles and to carry a plurality 95 of vehicles radially arranged thereon.

6. A parking floor for vehicles embodying an annular fixed floor area having radially arranged vehicle parking spaces and a diametrical driveway, an annular rotary vehicle-transporting table forming an annular floor area surrounding said fixed floor and having radially arranged vehicle parking spaces, and a fixed floor area surrounding 100 said rotary table and having radially arranged vehicle parking spaces and an exit and entrance driveway. 105

7. A vehicle parking floor embodying an annular movable area formed by a rotary vehicle transporting and parking table, a 110 fixed area surrounded by said table, and an annular fixed area surrounding said table and arranged with respect thereto to provide long and short approximately radially arranged vehicle parking spaces. 115

8. A vehicle parking floor embodying a rotary annular vehicle transporting area provided with supporting and propelling means and constructed and arranged to carry a plurality of radially arranged vehicles, and fixed floor areas surrounded by and surrounding said rotary area and approximately flush therewith for travel of vehicles onto and from said rotary area and providing a vehicle driveway to and from an 120 entrance and exit and across said rotary and central areas. 125

9. A vehicle parking floor having an annular depressed trough having fixed rails, and a rotary vehicle transporting table 130

- forming an annular portion of the floor and embodying an annular series of wheeled trucks coupled together and having supporting wheels traveling on said rails, said table having propelling means including a rack and a propelling shaft having operating means.
10. A vehicle parking and storing floor embodying fixed and rotary vehicle parking and driveway areas, the rotary area embodying an annular vehicle transporting and parking table adjacent to said fixed parking areas.

RUPERT SWINNERTON.
